JEWELRY BOX OR THE LIKE

William J. Reilly, Attleboro, Mass.

Application April 4, 1958, Serial No. 50,339

Term of patent 14 years

(Cl. D58—11)

FIG. 2

FIG. 3

Fig. 1 is a perspective view of a jewelry box showing my new design with the cover in open position;

Fig. 2 is a perspective side view thereof with the cover in closed position; and

Fig. 3 is a sectional view taken substantially through the central portion of the box on a reduced scale.

The broken lines indicate that the trim at the junction of the two halves of the box is in fact continuous and the side of the box not shown is the same as the side shown.

I claim:

The ornamental design for a jewelry box or the like, substantially as shown and described.
